 Bendix Aviation Corporation, South Bend, Ind.,
 a corporation of Delaware

Application January 27, 1942, Serial No. 428,350

7 Claims. (Cl. 74—7)

The present invention relates to engine starter gearing and more particularly to a detent for ensuring traversal of a starter pinion into mesh with a member of an engine to be started.

In those forms of starter drive involving a pinion arranged to be traversed into engagement with an engine gear by a threaded connection with the starting motor, some form of detent is sometimes desirable for temporarily resisting rotation of the pinion to ensure its traversal.

It is an object of the present invention to provide a novel detent for a starter pinion which is mechanically actuated as an incident to the operation of the starter switch.

It is another object to provide such a device which is arranged to cause the detent to engage the pinion momentarily concurrently with closure of the starting switch.

It is another object to provide such a device in which the detent is retracted from the pinion as a consequence of final movement of the switch-closing means.

It is another object to provide such a device in which the detent is thereafter held retracted until after release and re-actuation of the starting switch.

Further objects and advantages will be apparent from the following description taken in connection with the accompanying drawing, in which:

Fig. 1 is a semi-diagrammatic illustration of a starting system embodying the present invention, showing the starting switch and detent actuating means in side elevation partly broken away and in section;

Fig. 2 is a similar view of the switch and detent mechanism showing the parts in the positions assumed when the starting switch is closed and the detent ready to trip;

Fig. 3 is a similar view showing the positions of the parts during the cranking operation of the engine, and

Fig. 4 is a detail of the detent and pinion in end elevation.

In Fig. 1 of the drawing there is illustrated a starting circuit including a battery 1 grounded at 2 and connected by a lead 3 to a starting switch indicated generally by numeral 4. The switch is connected by a lead 5 to a starting motor SM which is grounded at 6 to complete the starting circuit. Switch 4 comprises a casing 7 in which stationary insulated contacts 8 and 9 are fixed in any suitable manner, and which casing is mounted as by means of a threaded sleeve 11 on a housing

member 12 which may be a portion of the housing of the starting motor.

A hollow plunger 13 is slidably mounted in the sleeve 11 and has pivoted thereon at its lower end, as indicated at 14, a curved detent member 15 which extends within the housing 12 adjacent a starting pinion 16, threaded on a screw shaft 17 adapted to be rotated by the starting motor SM. The detent 15 is formed as shown in Fig. 4 so as to be engageable between the teeth of the pinion 16 to resist rotation thereof and hence assure its traversal into operative position upon initial rotation of the screw shaft 17.

Plunger 13 is normally maintained in retracted position as illustrated in Fig. 1 by means of a spring 18, and means are provided for manually projecting the plunger to cause engagement of the detent 15 with the pinion 16, in the form of a push rod 19 coupled to the plunger 13 as indicated at 21 and having a push button or knob 22 fixed thereon at its upper end as shown at 23 and extending outside the casing 7 for convenient manipulation by the operator.

A switch member 24 is slidably mounted on the push rod 19 in position to engage and connect the contacts 8 and 9 of the starting switch when the push rod is depressed, such engagement being maintained while permitting further travel of the push rod by virtue of a spring 25 bearing on the contact 24 and against a shoulder 26 on the knob 22.

According to the present invention means are provided for causing the detent 15 to be retracted from the pinion 16 as a consequence to final downward movement of the plunger 13 after closure of the starting switch, and for thereafter maintaining the detent retracted until after release and re-actuation of the starting switch.

As here shown this is accomplished by forming a flattened surface 27 on the upper end of the detent 15, and providing a thrust block 28 slidably mounted within the hollow plunger 13 and pressed into engagement with the upper end of the detent by means of a spring 29. The flattened surface 27 is so located, as shown, that when the detent is in idle position the block 28 bears on the round portion of the detent and frictionally resists pivotal movement of the detent around its mounting pin 14. After initial pivotal movement has taken place, however, as illustrated in Fig. 2, the block 28 cooperates with the flattened surface 27 to cause further rotation of the detent and consequent withdrawal of the detent from the pinion.

In operation, starting with the parts in posi-

tion as illustrated in Fig. 1, depression of the knob 22 by the operator causes the detent 15 to be moved into engagement with the pinion 16 and then causes contact 24 of the starting switch to engage the fixed contacts 8 and 9 thus completing the starting circuit. The consequent rotation of the starting motor while the detent resists rotation of the pinion causes the pinion to be traversed into operative position. The further depression of the knob 22 by the operator causes the detent 15 to bottom on the root diameter of the pinion, and since its translatory movement is then obstructed, it is caused to turn on the pivot 14 into the position shown in Fig. 2. The plunger 28 then cooperates with the flat surface 27 of the detent to move the detent out of engagement with the pinion as shown in Fig. 3 where it is held during the cranking operation.

When the engine starts, release of the knob 22 by the operator permits the springs 18 and 25 to return the parts to their idle positions. Since the upper end of the detent 15 is shaped to conform with the opening in the lower end of the sleeve 11, the final return movement of the plunger 13 causes the detent to be rotated by its engagement with said sleeve into its normal position as shown in Fig. 1.

Rotation of the plunger and detent about the axis of the plunger is preferably prevented by any suitable means such as a pin 30 slidably mounted in a slot 31 in sleeve 11 so as to spline the plunger within said sleeve.

It will be noted by reference to Fig. 4 of the drawing that the contour of the detent is such that the teeth of the pinion will exert a camming force thereon when the pinion is positively rotated by the starting motor during the cranking operation. If the depression of the knob 22 by the operator is so slow that the pinion reaches its operative position before the plunger 13 is completely depressed, the pinion will therefore simply cam the detent out from between its teeth, and retraction of the detent by the block 28 will then take place in the usual manner.

Although but one embodiment of the invention has been described and shown in detail, it will be understood that other embodiments are possible and that various changes may be made in the design and arrangement of the parts without departing from the spirit of the invention as defined in the claims appended hereto.

What is claimed is:

1. In an engine starter a starting circuit including a motor and a starting switch, a screw shaft driven by the starting motor, a pinion having a threaded connection with the screw shaft, a detent for the pinion, and means for closing the starting switch and concurrently moving the detent into engagement with the pinion, said means including means whereby move-

ment thereof beyond the switch-closing position causes retraction of the detent from the pinion.

2. A starting system as set forth in claim 1 in which the retracting means for the detent holds said detent out of engagement with the pinion during the cranking operation and during the opening of the starting switch.

3. A starting system as set forth in claim 1 in which the detent is of such a contour that the teeth of the pinion will engage and cam the detent away from the pinion when the pinion is positively rotated by the motor.

4. In an engine starting system a starting circuit including a motor and a starting switch, a pinion, means actuating the pinion from the motor to engage and drive a member of an engine to be started, actuating means for the switch, means movably carried by the actuating means for momentarily engaging the pinion to resist rotation thereof, and means responsive to relative movement between the actuating means and the pinion-engaging means for retracting the pinion-engaging means.

5. In an engine starting system a starting circuit including a motor and a starting switch, a pinion having a threaded connection with the motor and movable thereby to engage and drive a member of an engine to be started, actuating means for the switch, a detent carried by the switch-actuating means and movable thereon into and out of operative position, means responsive to final closing movement of the switch-actuating means for moving the detent out of operative position, and means responsive to final opening movement of the switch-actuating means for returning the detent to operative position on said actuating means.

6. As an article of manufacture, a switch and pinion detent unit for engine starters including a casing having switch contacts fixed therein, a plunger movably mounted in the casing, a contact carried by the plunger and movable therewith to engage the fixed contacts, a detent mounted on the plunger for pivotal movement into and out of operative position, said detent having an arcuate surface and a flat surface, and yielding means engaging the arcuate surface of the detent for frictionally holding the detent in operative position and arranged to cooperate with the flat surface of the detent to rotate the detent to inoperative position when its movement with the plunger is obstructed.

7. A switch and detent unit as set forth in claim 6 including further, means for returning the detent to operative position with respect to the plunger responsive to switch-opening movement of the plunger.
